UNITED STATES PATENT OFFICE.

GEORGE A. MACBETH, OF PITTSBURG, PENNSYLVANIA.

DESIGN FOR A LAMP GLASS OR LENS.

41,093.

Specification for Design.

Patented Jan. 17, 1911.

Application filed August 24, 1910. Serial No. 578,805. Term of patent 14 years.

To all whom it may concern:

Be it known that I, GEORGE A. MACBETH, a citizen of the United States, residing at Pittsburg, in the county of Allegheny and State of Pennsylvania, have invented a new, original, and ornamental Design for Lamp Glasses or Lenses, of which the following is a specification, reference being had to the accompanying drawing, forming part thereof.

Figure 1 is a face view of the glass. Figure 2 is a perspective view of the same face.

I claim.

The ornamental design for a lamp glass or lens, as shown.

GEO. A. MACBETH.
